TUBE TRAILER

Lionel Wolpert, Fords, N.J., and Michael Tampa,
Yonkers, N.Y., assignors to Air Reduction Company,
Incorporated, New York, N.Y., a corporation of New
York

Filed Sept. 25, 1968, Ser. No. 13,710

Term of patent 14 years

Int. Cl. D12—10

U.S. Cl. D14—3

FIG. 1

FIG. 4

FIG. 5

FIGURE 1 is a perspective view of a tube trailer incorporating our new design;

FIGURE 2 is a left side elevational view of the trailer shown in FIGURE 1, the other side being substantially identical thereto;

FIGURE 3 is a plan view of the trailer shown in FIGURE 1;

FIGURE 4 is a rear elevation of the trailer shown in FIGURE 1; and

FIGURE 5 is a front elevation of the trailer shown in FIGURE 1.

We claim:

The ornamental design for a tube trailer, substantially as shown,
